UNITED STATES PATENT OFFICE.

ANDREW J. PLANTZ, OF APPLETON, WISCONSIN.

TIE FOR RAILWAY-RAILS.

1,113,825.

Specification of Letters Patent. Patented Oct. 13, 1914.

Application filed January 21, 1914. Serial No. 813,484.

To all whom it may concern:

Be it known that I, ANDREW J. PLANTZ, a citizen of the United States, residing at Appleton, in the county of Outagamie and State of Wisconsin, have invented new and useful Improvements in Ties for Railway-Rails, of which the following is a specification.

This invention is an improvement in metallic ties for supporting railway rails and devices adapted to retain the rails thereon and to secure the retaining means upon both the rail and tie and the invention resides in the construction, combination and arrangement of parts set forth in the following specification and falling within the scope of the appended claim.

In the drawing: Figure 1 is a central vertical longitudinal sectional view constructed in accordance with the present invention, the rails being arranged upon the tie, Fig. 2 is a detail top plan view of one of the ends of the tie, Fig. 3 is a transverse section on the line 3—3 of Fig. 1, Fig. 4 is a detail perspective view of one of the ends of the tie, and Fig. 5 is a similar view of one of the clamps.

The tie, as stated, is constructed of metal and is indicated by the numeral 1. The tie 30 may, and preferably does, comprise a hollow member and has its opposite sides inclined from its horizontally straight top to its bottom, as indicated by the numerals 2. The tie, adjacent the ends thereof is recessed 35 to provide a horizontally straight wall 3, one of the ends of which being vertically straight, as indicated by the numeral 4, and the second end being undercut to provide a rail engaging lip 5. The lip 5 is adapted 40 to engage with one of the base flanges of one of the rails R as well as with the portion of the web of the rail, as clearly shown in the drawing. The material forming the walls of said recess acts as a reinforcement 45 for the sides of the tie. The horizontally straight face 3 provided by each of the recesses is formed with a pocket 6 which is adapted to snugly receive a lug 7 formed upon a rail clamp 8. Each of these rail 50 clamps, above its lug, is of a thickness corresponding with the distance between the horizontal wall 3 and the top face of the tie 1, and the sides 9 of each of the clamps are beveled to conform with the beveled or

angular sides 2 of the tie 1. These clamps 55 8 are each integrally formed at one of their ends with a rail engaging lip 10, the said lip engaging with the base flange and web of the rail opposite that engaged by the lip 5 of the tie 1. The lug 7 is provided with 60 a transverse opening 11, and the tie 2 has an opening 12 which extends transversely thereof and intersects the longitudinal walls of each of the slots or openings 6, and passing through the said opening 12 as well as 65 the opening 11 in the lug 7, is a retaining element in the nature of a wedge-shaped bolt 13, the threaded end of the shank of the bolt being engaged by a nut 14, so that when the nut is tightened the wedge surface 70 of the bolt 13 forces the under surface of the lip 10 into tight contact with the rail base. The bolt 13 bears against the tie at four different places as indicated at 8^a, 8^b, 8^c and 8^d so that the strain that it is subjected to is distributed over its entire length. 75

From the above description, taken in connection with the accompanying drawing, the simplicity of the device, as well as the advantages thereof will, it is thought, be 80 perfectly apparent to those skilled in the art to which such invention appertains without further detailed description.

It is to be understood that my tie may be arranged at spaced intervals upon a track 85 between a number of the ordinary wooden ties and will prevent the spreading of the rails upon the said wooden tie. Also, if desired, a block of wood or other compressible material may be arranged upon my tie 90 and serve as a rest for the rails to absorb the shock and jar incident to the wheels of the rolling stock passing thereover.

Having thus described the invention, what I claim is:

A metallic tie and a rail engaging clamp, 95 said tie having its sides inclined from its top to its bottom, in an outward direction, the said tie adjacent its ends being recessed to provide a horizontal straight wall, a vertical wall and a rail engaging lip disposed 100 opposite the vertical wall, the horizontal wall being provided with a pocket, the metal forming the walls of the recess acting as a reinforcement for the sides of the tie, the 105 clamp completely filling said recess in the tie and having one of its ends straight and adapted to abut with the vertical wall of

the recess and its other end undercut to form a lip, the undersurface of the clamp having a depending apertured lug that snugly fits in the pocket in the tie, and a wedge member passing through the aperture in the lug and supported at intervals throughout its length by said tie.

In testimony whereof I affix my signature in presence of two witnesses.

ANDREW J. PLANTZ.
